William Augustus Berkley.

United States Patent Office.

WILLIAM AUGUSTUS BERKEY, OF GRAND RAPIDS, MICHIGAN.

Letters Patent No. 84,044, dated November 10, 1868.

IMPROVEMENT IN CONSTRUCTION OF FIRE-PROOF HOUSES.

The Schedule referred to in these Letters Patent and making part of the same.

To all whom it may concern:

Be it known that I, WILLIAM AUGUSTUS BERKEY, of Grand Rapids, Kent county, State of Michigan, have invented certain new and useful Improvements in the Construction of Buildings, to protect them, or the goods and furniture, from entire destruction by fire or water; and I do hereby declare that the following description and accompanying drawings are sufficient to enable any person skilled in the art or science to which they most nearly appertain to make and use my said improvements without further invention or experiment.

The object of my invention is to construct buildings, and use wooden joists or scantlings in their construction, and render the buildings and their contents secure against fire, and against damage by water applied to extinguish the fire, and stop fire, water, or sound from passing or communicating through the floors either up or down.

The nature of my invention and improvement consists in protecting the floor-joists, at the top or upper edge, from fire or water, or either, from passing down through; first, by laying deafening-floors between the joists near the top, and filling the space above the floor with mortar or cement even with the top of the joists, then laying strips of wood on the mortar or cement, between and parallel with the joists, and screwing them or fastening them to the deafening-floor, and filling the space between the strips of wood and over the joists with mortar or cement, and laying the floor-boards on the mortar or cement and strips, and fastening the boards to the strips, leaving the mortar unbroken, so that no wood exposed to the fire can communicate fire to the joists, and in protecting the floor-joists on the under edge from fire, by fastening iron plates or bars across them, and fastening the furring-strips to the under side of the iron, between the joists and ceiling or lathing, in to the furring, and applying a coat of mortar or cement above the ceiling or laths, (before the deafening-floor is laid,) to cover the furring and fill the spaces between the joists and ceiling or laths with mortar or cement, before applying the plastering to the under side of the laths, if wood ceiling is not used, if preferred. If preferred, nails or irons may be driven into the joists, to aid in holding the mortar to them.

And in protecting the joists or trimmers around the stairways or other openings from fire, by metal plates fastened to the joist or trimmers by brackets, so as to leave a space between the wood and the plates, and in setting the partitions, to prevent cracking the mortar or cement above the ceiling or laths, so as to avoid any openings at the top of the partitions for draught or air that would aid in communicating fire to the joist. To effect this, I fasten grooved or mortised strips under the ceiling or laths, to receive the upper ends of the boards or studs of the partition.

And in covering the beams which support the joists in buildings with sheet-iron fastened to the beam or

joists, so as to leave a space of about half an inch between the iron and the beam.

In the accompanying drawings—

Figure 1 is the plan of the walls and floor-joists of a building with my improvements.

Figure 2 is a section of fig. 1 on line z z.

Figure 3 shows a beam in section with joists, and the iron protection under the beam.

In the drawings, A A are the walls of the building; B B, the floor-joists, resting on or inserted in the walls in the usual manner.

In applying my improvements, I take hoop or other suitable iron, C, and punch it for the screws to hold the furring, and for the nails to fasten it to the joist. I then nail the strip or cleats B' B' on the side of the joists, then nail the irons C across the under edges of the joists, and nail or screw the furrings D D to the under side of the iron, between the joists, and fasten the ceilings under the furring, if ceiling is used; but, if board ceiling is not used, laths, E E, are made fast to the under side of the furring, and plastered, as usual. In order to give better clinch to the plastering, nails or other irons, F F, are driven into the lower corner of the joists; and if there are stairways or other openings, G, to be left in the floor, I set iron plates, H H, around such openings, about one and a half inch from the joists and trimmer I, and fasten them to the joists and trimmer by iron brackets, J J, as shown in the drawings. These iron plates H should be wide enough to extend from the bottom of the ceiling to the top of the floor.

I now prepare some mortar or cement, so that it will run freely, and pour it on to the furring and ceiling or laths, so as to fill all the spaces between the ceiling or laths and the lower edges of the joists, and cover the top of the furring about half an inch deep, and fill all the crevices and interstices from wall to wall, or from the wall to the iron plates H, with the mortar or cement, making an entire layer of fire-proof material, nearly or quite water and air-tight, which effectually protects the under edges of the joists from fire.

When the laths are used, they should be plastered first on the under side, or some boards pressed up against them, to protect the mortar from running through between the laths.

I now lay the deafening-floor K, so that the top of the floor will be about three-fourths of an inch below the top of the joists, and then fill the space on the floor between the joists with mortar or cement, poured on thin, and scraped and spread even with the tops of the joists.

I now take some furring-strips, L L, two inches wide and about one and a half inch thick, more or less, and fasten them on the mortar, half way between and parallel with the joists, by screws or nails, so as to nail the floor to these strips L L without breaking the mortar under them.

I now fill the spaces between the furring-strips with mortar or cement, M M, so as to cover the joists, and also to fill the spaces between the iron plates H H and joists and trimmers up even with the top of the furring-strips L L, and scrape it off even with the tops of the furring-strips L L, thus forming a complete layer or sheet of mortar or cement above the deafening-floor and joists from wall to wall, except the opening G, surrounded and protected by the iron plates, which layer of mortar or cement is nearly or quite water and air-tight, a perfect protection for the tops of the joists and deafening-floor from fire or water.

Thus, it is clearly apparent, from the foregoing, that the joists are perfectly protected by an entire sheet of mortar or cement above and below, so that no fire can get to them, nor any water pass through the floors, to injure the contents or goods on the floors below.

When the joists have been protected, as above described, the floor may be laid and fastened to the furring-strips L L in the ordinary manner.

In fig. 3 of the drawings, P is the end of a beam, and Q Q the joists, supported by the beam.

R is a box or trough, of sheet-iron, with a flange, S, at one edge, to nail it to the under side of the joists, to hold it in place; or, the edge of the sheet may be left vertical, and a piece of thick leather, T, may be put behind the edge and the beam, and nails driven

through the iron and leather into the beam to hold it on.

The iron may be held a proper distance from the beam by a few nails driven into the beam, to hold the top of the partition.

I fasten some grooved or mortised strips, N, under the ceiling or lath, to receive and hold the top ends of the boards or studs of the partition.

What I claim as my invention, and desire to secure by Letters Patent, is—

1. The combination of the iron straps C and furring D with the joists B and lath E, for the purpose substantially as described.

2. The floor-strips L, when attached to the deafening-partition K, in the manner described, for allowing the mortar M to be interposed, in the manner and for the purpose substantially as described.

3. The combination of the construction for suspending the ceiling and the construction for sustaining the floor, as described, with the interposed mortar, for preventing the burning of the timbers in such construction, and the passing of water or sound, as set forth.

WILLIAM AUGUSTUS BERKEY.
